UNITED STATES PATENT OFFICE

ERNEST A. HOOPES, OF DES MOINES, IOWA

ELECTRIC SWITCH

Application filed August 17, 1931. Serial No. 557,557.

The object of my invention is to provide an electric switch of simple, durable and inexpensive construction.

More specifically it is my object to provide an electric switch without friction joints, in which there are no bearings or other surfaces subjected to friction during the operation of the switch, to thereby provide a switch which at all times is moved to its open or closed position by the same amount of applied pressure and not dependent upon the condition of various bearings and friction surfaces.

A further object is to provide a switch in which the switch is especially designed for use as an automatic switch and in which a minimum degree of change in pressure will operate the switch in both directions.

A further object is to provide a switch in which the element provided for applying pressure to the switch to open or close it may be given a relatively short length of movement.

A further object is to provide a switch in which, when the contact points are firmly and forcibly held in actual contact during the initial states of the movement of the pressure applying element to the switch, a relatively rapid opening movement of the switch is attained when the desired pressure has been applied.

My invention consists in the construction, arrangement and combination of the various parts of the device, whereby the objects contemplated are attained, as hereinafter more fully set forth, pointed out in my claims, and illustrated in the accompanying drawing, in which:

Figure 1 shows a side elevation of my improved switch with the contacts closed and the pressure applying element in its normal position.

Figure 2 shows a similar view with the pressure applying element moved to position just prior to the opening movement of the switch.

Figure 3 shows a similar view with the switch in open position, portions being shown in section.

Figure 4 shows a top or plan view of my improved switch.

Figure 5 shows an end elevation of same.

Figures 6, 7 and 8 show respectively sectional views on the lines 6—6, 7—7 and 8—8 of Figure 3; and

Figure 9 shows an isometric view of the supplemental spring.

Referring to the accompanying drawing, I have used the reference numeral 10 to indicate generally the base or frame of the switch. At one end there is a support 11 having a curved upper face and above it is a plate 12 having a curved lower face.

The main spring 13 is formed of a single piece of relatively thin spring metal, normally concavo-convex in cross section. One end of the spring is inserted between the support 11 and the plate 12, and firmly forced into position by the screw 14.

On the under side of the free end of the spring there is mounted a contact carrier 15, preferably a straight piece of insulating material flat on its surface adjacent to the spring. The spring and contact carrier are connected by a metal band 16 passed around them and held together by a rivet 17, and by this means the outer or free end of the main spring 13 will be flattened, as shown in Figure 6.

At the outer end of the contact carrier 15 is a contact point 18, and mounted on the base 10 is a coacting contact point 19. On the under side of the contact carrier 15 is a lever 20 fixed in position by the rivet 17 and standing spaced apart from the main spring 13 and projecting in a direction toward the support 11 for the main spring. Fixed to the free end of the lever 20 is a socket 21 having a tapered opening at its under side and a round projection 22 at its upper side projected above the lever.

Interposed between the lever 20 and the spring 13 is a supplemental, substantially U-shaped spring 23 formed with a notch 24. This notch receives the projection 22 and holds the supplemental spring 23 in position.

The means for applying pressure to the switch for moving it to open position comprises a rod 25 inserted in the socket 21, and having its lower end inserted in a socket 26

in a plate 27. Plates of this kind are now commonly employed in connection with that class of switches operated by fluid pressure diaphragms, and this plate 27 may be used 5 in connection with such diaphragms or any other means for applying pressure to the switch.

In practical operation, and assuming that the switch is in the position shown in Figure 10 1, with no pressure applied, then the main spring 13 on account of its concavo-convex shape will retain its straight line position during the time that a considerable pressure is applied to its outer end from the concave 15 side.

Assuming that pressure has been applied to the free end of the lever 20 in an amount sufficient to bring the parts to the position shown in Figure 2, the spring 13 has been 20 moved upwardly a slight amount by this pressure applied through the supplemental spring 23, which, it will be noted from an examination of Figure 2, has been considerably compressed.

25 During this movement, however, the pressure applied to the free end of the lever 20 causes the free end thereof to move upwardly and cause the main spring 13 at the point shown by the dotted lines 8—8 to flatten. It 30 can easily be bent at that point, and hence that point of the spring 13 has been bent slightly downwardly, as clearly shown in Figure 2, and the contact carrier has been held firmly in closed position during this 35 part of the movement.

When the pressure applied to the free end of the lever 20 is increased to a very slight amount over that required for bringing the parts to the position shown in Figure 2, then 40 some part of the main spring 13 assumes a straight line position, as shown at 6—6 in Figure 3, and when this position has been reached, the main spring 13 moves very freely in a switch opening position.

45 As soon as the main spring 13 flattens at one point, as shown at 6—6 in Figure 3, then the supplemental spring 23 expands and moves the contact carrier to relatively wide open position, and this wide open movement 50 of the contact carrier is accomplished with a relatively short movement of the pressure applying rod 25. The dotted lines in Figure 2 indicate the length of the movement of the plate 27 necessary to move the contact carrier 55 from the position shown in Figure 2 to the position shown in Figure 3.

It will be noted that in my improved switch there are no pivot bearings or surfaces to which it is necessary to apply friction. All 60 of the parts, except the springs themselves, can be made of material which will not rust or corrode, and the springs may be treated by any of the well known processes to prevent rust or corrosion.

65 Hence, with my improved switch there is

no necessity for lubrication and the rapid opening movement of the switch is never slowed up by the lack of lubrication or the accumulation of rust or corrosion on frictional surfaces thereof.

In practice I have found that with my improved switch, and when used in connection with an air pressure tank, a certain predetermined degree of pressure will move the switch to open position, and a relatively slight decrease in said pressure will move it to closed position.

I have also found in use that the length of movement of the pressure applying rod 25 required for moving the switch from the position shown in Figure 2, to that shown in Figure 3, is relatively small, and that a relatively small diaphragm may be employed for causing this small movement.

I do not desire to be understood as limiting my invention to its specific use in connection with electric switches, because obviously the carrier member may be utilized for purposes other than opening and closing the contacts of an electric switch.

I claim as my invention:

1. In an electric switch, the combination of a spring formed concavo-convex in cross section, means for supporting said spring at one end portion, a contact carrier on the free end portion of said spring, means for applying pressure to the concave side of said spring, and a supplemental spring interposed between the first mentioned spring and the said means for applying pressure.

2. An electric switch comprising a spring concavo-convex in cross section, means for supporting it at one end portion, a contact carrier having a flexible connection with the free end of said spring, a lever fixed to the contact carrier, means for applying pressure to said lever in a direction tending to move the contact carrier to open position, and a supplemental spring coacting with the contact carrier for increasing its opening movement.

3. An electric switch comprising a contact carrier, a spring having a concavo-convex portion and being connected with the contact carrier for normally holding it in its closed position, means for applying pressure to said spring tending to move the contact carrier to open position, and a supplemental spring placed under compression by the said pressure applying means and tending to increase the opening movement of the contact carrier.

4. An electric switch comprising a spring concavo-convex in cross section, means for supporting it at one end portion, a contact carrier having a flexible connection with the free end of said spring, a lever fixed to the contact carrier at one end, means for applying pressure to the free end of the lever in the direction required for causing the lever to hold the contact carrier to closed position

during the initial part of the movement of the spring toward open position.

5. An electric switch comprising a spring concavo-convex in cross section, means for supporting it at one end portion, a contact carrier having a flexible connection with the free end of said spring, a lever fixed to the contact carrier at one end, means for applying pressure to the free end of the lever in the direction required for causing the lever to hold the contact carrier to closed position during the initial part of the movement of the spring toward open position, and a supplemental spring between the free end 10 of the lever and the first mentioned spring shaped to be compressed by the movement of the lever toward the first mentioned spring and to expand during the opening movement of the contact carrier to thereby greatly increase the length of the opening movement of the contact carrier.

6. An electric switch comprising a frame, a contact point carried by the frame, a spring fixed at one end to the frame and having its 25 body portion concavo-convex in cross section, a contact carrier arm fixed to the other end of the spring, the end of the spring adjacent to said arm being substantially flat in cross section, a lever fixed to the contact carrier 30 arm and extending in substantially parallel spaced relation to the concave side of the said spring, a yielding pressure device interposed between said lever and said spring, and means for applying pressure to the free end 35 portion of said lever in a direction tending to force it toward the said spring

7. In an electric switch, the combination of a contact carrier formed of spring metal substantially straight longitudinally and substantially concavo-convex transversely, means for supporting it, and means for applying pressure to the concave side of the contact carrier in an amount sufficient to cause a portion of the contact carrier to assume a substantially straight line position transversely at one portion to thereby suddenly greatly reduce the resistance of the contact carrier at that portion, and to cause a rapid movement of a portion of the contact 50 carrier in the direction required for opening the switch.

8. The combination of a carrier member formed of spring metal substantially straight longitudinally and substantially concavo-convex transversely, means for supporting it, and means for applying pressure to the concave side of the carrier member in an amount sufficient to cause a portion of the carrier member to assume a substantially straight line position transversely at one point, to thereby suddenly greatly reduce the resistance of the carrier member at that point, and to cause a rapid movement of a portion of the carrier member in the direction in which said 60 pressure is applied.

9. The combination of a spring substantially straight longitudinally and substantially concavo-convex in cross section, means for supporting it at one end portion, a carrier member having a flexible connection with the free end of said spring, a lever fixed to the carrier member, means for applying pressure to the lever in the direction required for causing the lever to hold the carrier member in its original position during the initial part of the movement of the spring in the direction in which the pressure is applied to the lever.

10. The combination of a spring substantially straight longitudinally and substantially concavo-convex transversely, means for supporting it at one end, a carrier member fixed on the free end of the spring, said carrier member being normally in closed position when the spring is substantially straight and in open position when the spring has been moved from a substantially straight line position, and means for applying pressure to the concave side of the spring to move the carried member to open position.
